STAND AND METHOD OF MAKING
THE SAME

John R. Harris, New York, N. Y.

Application August 29, 1945, Serial No. 613,305

3 Claims. (Cl. 248—174)

1

This invention relates to paper or cardboard display stands adapted for use for carrying advertising display cards, placement cards and many other uses too numerous to mention.

One object of the invention is to provide a device of this nature made of a single sheet of heavy paper or cardboard, suitably scored and slitted and provided with interlocking parts, in such manner that the stand may be erected and held together without the use of glue or paste.

Another object of the invention is to provide such a polygonal stand which will stand upright without any danger of its being upset even though it supports or carries a considerably tall display object.

A further object of the invention is the provision of such a device, a great number of which may be piled up and shipped and stored flat so as not to take up too much space.

Still another object of the invention is to produce a device of this nature which readily lends itself to be suitably ornamental and form a complete symmetrical design when erected.

Another object is to produce a device of the character described in which the maximum simplicity of construction and operation is secured.

Other objects and advantages will appear as the nature of the invention is better understood, the invention consisting substantially in the novel arrangement and co-relation of parts herein fully described, and illustrated in the accompanying drawings, wherein similar reference characters are used to describe corresponding parts throughout the several views, and then finally pointed out and specifically defined in the appended claims.

The disclosure made the basis for exemplifying the present inventive concept suggests a practical embodiment thereof, but the invention is not to be restricted to the exact details of this disclosure, and the latter, therefore is to be understood from an illustrative, rather than a restrictive standpoint.

In carrying out a preferred embodiment of the present invention, it has been found advantageous to blank out a strip of cardboard, score and slit same so that it may be formed into a polygonal stand and the base and walls thereof held together without the use of glue or the like.

In the drawings:

Figure 1 is a perspective view of a preferred embodiment of the present invention;

Figure 2 is a bottom plan view thereof;

Figure 3 is a cross sectional view taken along line 3—3, Fig. 1;

2

Figure 4 is a fragmental sectional view taken on line 4—4, Fig. 2.

Figure 5 is a face view of the blank in unfolded position;

Figure 6 is a top plan view of a modified form of the invention and

Figure 7 is a face view of the blank from which the same is formed.

Referring now to Figs. 1 to 5 of the drawings, 10 indicates a stand made of a paper or cardboard blank 11 and folded into a substantial tetrahedron. The blank 11 comprises a body forming section 12 having diagonal scoring lines 13 and 14 which divide said body forming section into substantially triangular walls 15, 16, and 17 and a backing 18 for the wall 16. A two ply bottom forming section 19 is formed along the bottom edge of the wall 16 (see Figs. 2, 3, and 5). Said bottom forming section comprises a wall 20 hingedly connected to the wall 16 along two short score or fold lines 21 and 22, and a second wall 23 extending from the wall 20 along a score line 24. The bottom forming section 19 is partially severed from the body forming section 12 by means of slits 25 and 26.

The wall 16 is severed from the wall 18 along a partly straight and partly curved cut 27, the curved or arcuate portion of the cut forms a locking tab 28 bendable from the wall 16 along 30 the score line 13^a which is a continuation of line 13. The locking tab 28 co-acts with a slit 30 as will later be explained. The backing wall 18 has a triangular cut out 31 and the walls 15, 16 and 17 are respectively provided with triangular tongues 32, 33, 34. A leg 35 is formed at the intersection of walls 15 and 16, a similar leg 36 is formed at the intersection of wall 17 and backing 18 and a third similar leg 37 is formed at the intersection of the walls 15 and 17 and finally an auxiliary base 38 is formed at the lower edge of the wall 15. The said base may extend as shown or across the entire lower edge of the said wall 15. The said base is partially severed from the wall 15 by a cut out portion 39 and is bendable along a pair of short score lines 40—41.

As may be seen by referring to Figs. 1 and 5 the body portion of the device is ornamented by way of illustration with a blue background, 50 white stars and red legs.

To form the stand 10, the body portion may be folded or bent downwardly along lines 13, 13^a and 14. The wall 16 is swung over the backing 18 until the tab 28 engages the slit 30 and is locked therein, the wall 23 is then folded back

against the wall 20 along line 24, and then the wall 20 may be folded under the body portion along lines 21 and 22. Tab 33 is forced into cut out 31 to further lock the backing 18 and wall 16 together and tabs 32 and 34 act to support the double ply bottom 19 in place. The base 38 is bent up and the stand is in position to support any suitable display. In the present instance a flag 41 whose flag pole 42 is shown as extending through holes formed by star-like slits 43, 44, and 45 formed respectively in the apex of the body and walls 20 and 23 of the bottom.

In the modified form of the invention shown in Figs. 6 and 7, there is shown a stand 50 of a substantial hexahedron shape, having a pyramidal body of five triangular walls or sides 51, 52, 53, 54, and 55. As in the preferred form of the invention the entire stand is made from a single blank 56 and is subdivided into said walls and a backing portion 57 by score lines 58, 59, 60 and 61 and 62 radiating from the center of a substantially hexagonal body forming portion 63. The backing portion 57 is severed from the wall 54 by a composite straight and curved slit 64, the curved portion of the cut or slit forming a locking tab 65 co-operating with a slit 65^a to lock the body together when the same is in folded or erected position. A pentagonal bottom wall 66 is foldable from the wall 54 along fold or score lines 67 and 68, cuts or slits 69 and 70 partially severing the bottom wall from the wall 54 and permits said folding. An auxiliary base 71 bendable from the wall 53 along lines 72 and 73 is provided for extra support for the stand. Tabs 74 struck from each of the walls act to support the base or bottom wall 66 when in folded position. A triangular cut out 74^a in backing portion 57 permits the tab 74 of wall 54 to pass through the said cut out to support the base. The body and bottom wall may be punctured or slitted at 75 and 76 respectively to form alined openings for supporting a rod or the like carrying advertising display means or the like.

From the foregoing it will be seen that the display stand of the present invention is of simple, inexpensive construction and is readily adaptable for use in supporting advertising display signs, placement cards or decorations of various kinds.

It will also be seen that the stand may be shipped and stored in flat unfolded position and may readily be erected or knocked down as and when desired.

What is claimed is:

1. A pyramidal paper or cardboard stand made from a single blank, comprising a plurality of triangular side walls hingedly connected to one another along a score line, a backing member hingedly connected to one of said walls and severed from the next wall adjacent thereto, the hinge connection between the backing member and its adjacent wall being formed with a slit, a locking tab on the wall severed from the backing member adapted to co-operate with the slit for locking said last mentioned walls together,

a bottom wall partially severed from and foldably connected to the tab carrying wall, and bottom wall supporting tabs struck from said side walls.

5. 2. A pyramidal paper or cardboard stand made from a single blank, comprising a plurality of triangular side walls hingedly connected to one another along a score line, a backing member hingedly connected to one of said walls and severed from the next wall adjacent thereto, the hinge connection between the backing member and its adjacent wall being formed with a slit, a locking tab on the wall severed from the backing member adapted to co-operate with the slit for locking said last mentioned walls together, a two ply bottom wall, comprising a section partially severed from and foldably connected to the tab carrying wall, a second section foldably connected to the first mentioned section, and tabs for supporting said bottom wall in folded position, said tabs being struck from said side walls.
- 10 3. A pyramidal paper or cardboard stand made from a single blank for supporting a flag pole, comprising a plurality of triangular side walls hingedly connected to one another along a score line, a backing member hingedly connected to one of said walls and severed from the next wall adjacent thereto, the hinge connection between the backing member and its adjacent wall being formed with a slit, a locking tab on the wall severed from the backing member adapted to co-operate with the slit for locking said last mentioned walls together, a bottom wall partially severed from and foldably connected to the tab carrying wall, legs formed at the intersections of said walls, tabs for supporting said bottom wall in folded position, said tabs being struck from said side walls, and an auxiliary base extending from one of said side walls, said bottom wall being at a higher level than the bottom of said legs, said side walls having star-like slits formed in the apex thereof, said bottom wall having star-like slits formed therein in alinement with said first mentioned star-like slits, whereby said pole passed through said star-like slits is supported by said side walls and said bottom wall.

JOHN R. HARRIS.
